(57) **CLAIM**

The ornamental design for a gaming machine component, as shown and described.

DESCRIPTION

FIG. 1 is a front, top, right side perspective view of a gaming machine component showing our new design;

FIG. 2 is a top plan view thereof;

FIG. 3 is a right side elevation view thereof, the left side being a mirror image; and,

FIG. 4 is a bottom view thereof.

The features shown in broken lines form no part of the claimed design.

1 Claim, 4 Drawing Sheets
